UNITED STATES PATENT OFFICE.

ROBERT C. SPRAGUE, OF QUINCY, MASSACHUSETTS.

TONE-CONTROL MEANS.

Application filed May 29, 1925. Serial No. 33,724.

My present invention relates to sound reproducing apparatus, particularly electrically operated sound reproducing apparatus, more particularly radio signalling apparatus, and specifically to a tone control means for audio frequency currents.

In radio signaling apparatus in use at the present day, and particularly that class of radio signaling apparatus known as radio 10 telephone receiving sets, no effective way has been discovered of suitably varying the tone of the receiving instruments as telephone receivers or loud speakers. By means of my present apparatus I am able to positively and accurately vary the tone of the 15 telephone receivers or loud speakers, and as this is the first means of which I am aware for producing this desired result, I desire to claim the same broadly. In carrying out my 20 invention, I utilize a condenser, and preferably a variable condenser, across or in shunt with the telephone receiver or loud speaker and, by varying the capacity of the condenser, am enabled to control the tone of the 25 telephone receivers or loud speakers. When once the desired tone has been produced I can, by measuring the capacity of the condenser, substitute for the variable condenser a fixed condenser of that known capacity. 30 In this connection, I am aware that it is a common expedient to use a condenser in shunt across the telephone receivers or a radio receiving set, but my invention is to be differentiated therefrom as such condensers as have heretofore been used are not used for the purpose for which my apparatus is used, nor could they be used for such purpose, having ordinarily too small a 35 capacity.

40 In the accompanying drawings illustrating a preferred embodiment of my invention,

Fig. 1 shows a non-regenerative detector circuit employing a three element audion 45 tube, and

Fig. 2 shows a modified form of Fig. 1 and to which has been added a single stage of audio frequency amplification.

Referring to the drawings, and particularly to Fig. 1 wherein is shown a single circuit non-regenerative detector circuit employing a three element audion tube, 10 designates an audion tube, the plate 11 of which is connected to a B battery 12 and to a pair 55 of telephone receivers 13 and thence by conductor 14 to the filament 15. The circuit

from plate 11 through B battery 12, telephone receivers 13, conductor 14 and filament 15 is commonly known as the plate circuit. The current in the plate circuit is, 60 as is well known, made up of two components, one of radio frequency and one of audio frequency. The audio frequency current is capable of operating the telephone receivers. A circuit as thus described will 65 usually operate satisfactorily, due to the capacity of the telephone leads and telephone winding itself, through which the radio frequency component of current may bypass the high inductance of the telephones 70 13; but it is sometimes necessary, and often advantageous to introduce between the points 16 and 17 an additional capacity 18 for this purpose; namely, to provide a means, so that the radio frequency component of current may by-pass the high inductance 75 of the telephones 13. This capacity is usually in the form of a small condenser, and, as shown, is shunted across the telephones 13. The use of such condenser as 18 80 has been known for a long time and it is ordinarily called the phone condenser. In use, it has a customary value of from 0.002-0.004 of a microfarad. While the condenser 18 could be made variable, this is not the 85 usual custom. As above stated, it is possible to operate this circuit without the use of a condenser 18, and this is true particularly if the telephone leads from the battery 12 and filament 15 to the telephones are of 90 considerable length. By the use of the condenser 18, however, the radio frequency component of the current in the plate circuit above referred to is by-passed and practically none of such component passes into 95 the conductors leading to the telephones 13. Therefore, the only component of the current in such telephone 13, or in the direct circuit leading thereto, is the audio frequency component. This being so, it will 100 be obvious that, no means having been specially provided for affecting the audio frequency component, the use of the condenser 18 can have no effect whatever on the tone produced on the telephone receivers 13 by 105 such audio frequency component.

Referring now to Fig. 2 wherein is shown the simple receiving circuit of Fig. 1 with the addition thereto of a single stage of audio frequency, that portion of Fig. 2 110 where the elements therein are identical with the like elements in Fig. 1 have been

given the same reference characters. From the reasoning as applied to Fig. 1 it is evident, therefore, that, if the telephone 13 has substituted therefor, as it has in Fig. 2, the 5 primary winding 19 of an audio frequency transformer, the only component of the current in the plate circuit passing through such primary will be the audio frequency component. The best audio frequency transformers are only designed to pass on audio frequency impulses between the range of 10 50-10,000 cycles per second. The radio frequency impulses, which are of the order of 1,000,000 cycles per second, being choked out 15 of the amplifying circuit and by-passed through the separate condenser in Fig. 2 or, if the circuit is properly designed, the condenser 18 in Fig. 2 may be dispensed with and dependence placed on the capacity of 20 the primary winding 19. The secondary winding 20 of the transformer is in circuit with the three element audio tube 21 and into the plate circuit thereof, such plate circuit consisting of a plate 22, B battery 23, 25 loud speaker 24, conductor 25, and the filament 26. The only current in the plate circuit last described is the alternating current of audio frequency and, therefore, there is no need of a by-pass condenser between the 30 points 27 and 28 of such circuit as existed for the by-pass condenser 18 between the points 16 and 17 in either Fig. 1 or Fig. 2 to insure proper electrical operation of the set. Perhaps it is for this reason that, heretofore 35 no condenser, either fixed or variable, has been found necessary in the situation just referred to for, as stated above, the use of the condenser is a by-pass condenser to pass the radio frequency component of current around the telephone receivers and allow only the audio frequency component to pass through such receivers. I have found, however, that if a variable condenser of 40 proper capacity, as the condenser 29, is shunted across the loud speaker or telephones 24, at the points 27 and 28, a control

is obtained over the tone of the telephone receiver or loud speaker 24, and by experimentation I have found that the capacity of the condenser 29 should vary approximately 50 from 0.01-0.05 of a microfarad. The use of the tone control condenser in all cases has greatly improved the quality of the tone of the instrument and thus my device is capable of having the tone of the instrument 55 placed under control of the operator. This phenomenon of tone control is practically due to the carrying over and broadening of the tones as the tone control condenser changes the phase angle of the audio frequency current that passes through the loud speaker or telephones 24.

The capacity of a tone control condenser is approximately 0.01-0.05 of a microfarad. The phone condenser is used as a radio frequency current by-pass. The tone control condenser is used to control the tone of the receiving instrument.

Having thus described my invention, what I claim as new is:

1. An improved tone control for radio receiving circuits, comprising an output circuit, means for delivering audio frequency current thereto, telephone receiving instruments in series in said circuit, and a variable condenser of from 0.01 to 0.05 of a microfarad capacity in shunt to said receiving instruments.

2. The improved method of controlling the tone of the translating instruments of 80 radio receiving circuits, which consists in delivering to said instruments only alternating currents of audio frequency, by-passing a portion of said currents through a variable capacity of approximately from 0.01 to 0.05 85 of a microfarad connected in shunt to said instruments and varying said capacity within the above limits to obtain the tone desired.

In testimony whereof, I have signed my name to this specification.

ROBERT C. SPRAGUE.
